United States Patent Office

Des. 205,260
Patented July 12, 1966

205,260

COMBINED STORAGE AND DISPLAY CABINET, REFRIGERATOR AND COOKING UNIT

Frank X. Blasco, Kansas City, Mo., assignor to Chic-N-Krisp, Inc., Kansas City, Mo., a corporation of Missouri

Filed Aug. 25, 1965, Ser. No. 86,717

Term of patent 14 years

(Cl. D81—10)

Fig. 1.

FIG. 2.

FIG. 3.

FIG. 1 is a front perspective view of a combined storage and display cabinet, refrigerator and cooking unit embodying my new design;

FIG. 2 is a plan view of same; and

FIG. 3 is an end elevational view of same, the opposite end elevation being the same.

I claim:

The ornamental design for a combined storage and display cabinet, refrigerator and cooking unit, as shown and described.
